(57) **CLAIM**

The ornamental design for straps with enclosure, as shown and described.

DESCRIPTION

FIG. 1 is a front perspective view of straps with enclosure showing our new design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a front perspective view of straps with enclosure showing our new design in a second embodiment;

FIG. 9 is a top view thereof;

FIG. 10 is a bottom view thereof;

FIG. 11 is a front view thereof;

FIG. 12 is a rear view thereof;

FIG. 13 is a right side view thereof;

FIG. 14 is a left side view thereof;

FIG. 15 is a front perspective view of straps with enclosure showing our new design in a third embodiment;

FIG. 16 is a top view thereof;

FIG. 17 is a bottom view thereof;

FIG. 18 is a front view thereof;

FIG. 19 is a rear view thereof;

FIG. 20 is a right side view thereof;

FIG. 21 is a left side view thereof;

FIG. 22 is a front perspective view of straps with enclosure showing our new design in a fourth embodiment;

FIG. 23 is a top view thereof;

FIG. 24 is a bottom view thereof;

FIG. 25 is a front view thereof;

FIG. 26 is a rear view thereof;

(Continued)

FIG. 27 is a right side view thereof; and,
 FIG. 28 is a left side view thereof.
 The broken lines at the ends of the straps depict the
 boundaries of the claim, while all other broken lines depict
 portions of the claim that form no part of the claimed design.

1 Claim, 28 Drawing Sheets
